The 8 Best Self-Emptying Robot Vacuums, According to Thousands of Reviews, available in <https://news.yahoo.com>, announced Year Dec. 22, 2021 [online], [site visited Feb. 19, 2024], Internet URL: <https://news.yahoo.com/8-best-self-emptying-robot-211450539.html> (Year: 2021).*

Primary Examiner — Jennifer Rivard*Assistant Examiner* — JennyLou M Binas(74) *Attorney, Agent, or Firm* — Grossman, Tucker, Perreault & Pfleger, PLLC(57) **CLAIM**

The ornamental design for a robot vacuum, as shown and described.

DESCRIPTION

FIG. 1 is a front view of a robot vacuum, showing the new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a front, top right perspective view thereof;

FIG. 8 is a front, top left perspective view thereof;

FIG. 9 is a front, bottom right perspective view thereof;

FIG. 10 is a front, bottom left perspective view thereof;

FIG. 11 is a rear, top left perspective view thereof;

FIG. 12 is a rear, top right perspective view thereof;

FIG. 13 is a rear, bottom right perspective view thereof; and,

FIG. 14 is a rear, bottom left perspective view thereof.

The broken lines in the figures show portions of the robot vacuum that form no part of the claimed design.
